(57) **CLAIM**

The ornamental design for a medical instrument, substantially as shown and described.

DESCRIPTION

FIG. 1 is a perspective view of a medical instrument in accordance with our new design;

FIG. 2 is a left side view thereof;

FIG. 3 is a right side view thereof;

FIG. 4 is an enlarged front view thereof;

FIG. 5 is a top view thereof; and,

FIG. 6 is a bottom view thereof.

The broken lines in the drawing depict portion of the medical instrument and form no part of the claimed design.
